BUILDING

CROSS REFERENCE TO RELATED APPLICATIONS

This Application is a national stage filing under 35 U.S.C. 371 of International Patent Application Serial No. PCT/JP2020/030316, filed Aug. 7, 2020, entitled "BUILDING." The entire content of this application is incorporated herein by reference in its entirety.

TECHNICAL FIELD

The present invention relates to a building.

BACKGROUND

Patent Literature 1 discloses the structure of a building. Patent Literature 1 also discloses a method for fastening members included in a floor of the building. For example, steel framing components are arranged above and along a wall, and joist webs are fastened to the steel framing components.

CITATION LIST

Patent Literature

Patent Literature 1: U.S. Patent Application Publication No. 2004/0200172

SUMMARY OF INVENTION

Technical Problem

In a wooden building, there is room for improvement in earthquake resistance of the floor structure between the upper and lower floors. Thus, a building including a highly earthquake-resistant floor is provided.

Solution to Problem

(1) A building that solves the problem includes a floor located between an upper floor and a lower floor. The floor includes first floor extending members and second floor extending members that intersect the first floor extending members. The first floor extending members and the second floor extending members are made of wood. A reinforcement member is arranged in at least one of a section between two of the first floor extending members and a section between two of the second floor extending members. In this configuration, the reinforcement members further reinforce a frame assembly including the first floor extending members and the second floor extending members. This makes the floor more resistant to earthquake.

(2) In the building according to (1), the reinforcement member is arranged between the two of the first floor extending members. The two of the first floor extending members each include a support metal fitting that supports an end of the reinforcement member. The reinforcement member is supported by the support metal fittings that are respectively arranged at the two of the first floor extending members. This configuration allows the floor to be reinforced through a simple attachment task.

(3) In the building according to (1) or (2), the reinforcement member is arranged between the two of the second floor extending members. The two of the second floor

2

extending members each include a support metal fitting that supports an end of the reinforcement member. The reinforcement member is supported by the support metal fittings that are respectively arranged at the two of the second floor extending members. This configuration allows the floor to be reinforced through a simple attachment task.

(4) In the building according to (3), a cross-section of the reinforcement member is shaped so as to include a first portion extending vertically and a second portion arranged on each of opposite sides of the first portion and intersecting the first portion. This configuration reduces flexing of the floor in the vertical direction.

(5) In the building according to any one of (1) to (4), the first floor extending members, the second floor extending members, and the reinforcement member are arranged such that upper surfaces of the first floor extending members, upper surfaces of the second floor extending members, and an upper surface of the reinforcement member are flat surfaces flush with each other. This configuration defines a flat floor surface.

Advantageous Effects of Invention

25 The above building makes the floor more resistant to earthquake.

BRIEF DESCRIPTION OF DRAWINGS

30 FIG. 1 is a schematic diagram showing a building. FIG. 2 is a perspective view showing the skeleton frame of the building body.

FIG. 3 is a perspective view showing the foundation metal fitting.

35 FIG. 4 is a perspective view showing the first coupling metal fitting.

FIG. 5 is a perspective view showing the second coupling metal fitting.

40 FIG. 6 is a perspective view showing the third coupling metal fitting.

FIG. 7 is a perspective view showing the floor.

FIG. 8 is an exploded perspective view showing the floor.

45 FIG. 9 is a cross-sectional view showing the reinforcement member.

FIG. 10 is a perspective view showing the roof.

FIG. 11 is a side view showing the roof frame.

FIG. 12 is a perspective view showing a portion where the roof frame is coupled to the roof horizontal member.

50 FIG. 13 is a perspective view showing a portion where the roof frame is coupled to the roof horizontal member.

FIG. 14 is a perspective view showing a portion where the roof frame is coupled to the roof horizontal member.

DESCRIPTION OF EMBODIMENTS

55 A building will now be described with reference to FIGS. 1 to 14. The building of the present embodiment has two floors. FIG. 2 shows the skeleton frame of the first-floor section of a building 1. FIG. 2 does not show reinforcement members 63 at a floor 60 that is located between the first and second floors.

As shown in FIG. 1, the building 1 includes a foundation 2, a building body 3, and a roof 4. The building 1 of the present embodiment has multiple floors. The foundation 2 is arranged on the ground. The foundation 2 is made of, for example, reinforced concrete. The building body 3 is arranged on the foundation 2.

As shown in FIG. 2, the building body 3 has a Rahmen structure. More specifically, the building body 3 includes vertical members 10, first lateral members 11, and second horizontal members 12. The vertical members 10 are also referred to as posts. The vertical members 10 are made of wood. The vertical members 10 are arranged upright on the foundation 2 using foundation metal fittings 20.

The vertical members 10 may have a length extending over multiple floors. The vertical members 10 may have a length equivalent to the height of one floor. The lower end face of each vertical member 10 includes a slit 10c into which a plate 23 of the corresponding foundation metal fitting 20 is inserted. The slit 10c extends from an end face 10a of the vertical member 10 in a longitudinal direction of the vertical member 10. Thus, the inner surface of the slit 10c is arranged with the grain of the vertical member 10. This limits a decrease in the strength of a portion branched by the slit 10c. Slits 11c, 12b, which will be described below, have the same structure. That is, in a member including the slit 11c and a member including the slit 12b, the slits 11c, 12b each extend in a longitudinal direction of the corresponding member from its end face perpendicular to the longitudinal direction of the member.

As shown in FIG. 3, the foundation metal fitting 20 includes a fixed portion 21 fixed to the foundation 2, a receiving portion 22 located above the fixed portion 21, and the plate 23 extending upward from the receiving portion 22. The receiving portion 22 receives the end face 10a of the vertical member 10. The fixed portion 21 of the foundation metal fitting 20 is fixed to the foundation 2 using a bolt. The plate 23 of the foundation metal fitting 20 is fixed to the vertical member 10 using drift pins 24. The drift pins 24 are inserted into the vertical member 10 so as to extend through the plate 23 and the vertical member 10 in a state of being placed in the slit of the vertical member 10.

Each first horizontal member 11 extends across multiple vertical members 10. The first horizontal member 11 is a longitudinal beam or a transverse beam. In one example, the first horizontal member 11 is arranged such that a side surface 11b of the first horizontal member 11 is in contact with the end face 10a of the vertical member 10 (see FIG. 4). In another example, the first horizontal member 11 is arranged such that an end face of the first horizontal member 11 is in contact with a side surface 10b of the vertical member 10. In a further example, the first horizontal member 11 is arranged such that the end face of the first horizontal member 11 is in contact with a side surface of the second horizontal member 12.

The second horizontal members 12 intersect the first horizontal members 11. Each second horizontal member 12 extends across multiple first lateral members 11. The second horizontal member 12 is a longitudinal beam or a transverse beam. In one example, the second horizontal member 12 is arranged such that an end face 12a of the second horizontal member 12 is in contact with the side surface 11b of the first horizontal member 11 (see FIG. 5). In another example, the second horizontal member 12 is arranged such that the end face 12a of the second horizontal member 12 is in contact with the side surface 10b of the vertical member 10.

The vertical members 10 are coupled to the first horizontal members 11 using coupling metal fittings. The first horizontal members 11 are coupled to the second horizontal members 12 using coupling metal fittings. The vertical members 10 are coupled to the second horizontal members 12 using coupling metal fittings. Examples of the coupling metal fittings include first to third coupling metal fittings 30 to 40, which will be described below.

As shown in FIG. 4, the first coupling metal fitting 30 couples the vertical member 10 to the first horizontal member 11. The first coupling metal fitting 30 may couple the vertical member 10 to the second horizontal member 12.

The first coupling metal fitting 30 includes a tenon protrusion 31 and a plate 32 on the tenon protrusion 31. The tenon protrusion 31 is configured to be fitted to a tenon hole 11d of the first horizontal member 11. The plate 32 is configured to be inserted into the slit 10c of the vertical member 10. The tenon protrusion 31 is fixed to the first horizontal member 11 using drift pins 24. The plate 32 is fixed to the vertical member 10 using drift pins 24.

As shown in FIG. 5, the second coupling metal fitting 36 couples the second horizontal member 12 to the vertical member 10. The second coupling metal fitting 36 may couple the second horizontal member 12 to the first horizontal member 11.

The second coupling metal fitting 36 includes a fixed portion 37 that is fixed to the vertical member 10 or the first horizontal member 11 and a plate 38 that extends from the fixed portion 37. The fixed portion 37 is fixed to the side surface 10b of the vertical member 10 or the side surface 11b of the first horizontal member 11 using a bolt. The plate 38 is configured to be inserted into the slit 12b of the second horizontal member 12. The plate 38 is fixed to the second horizontal member 12 using a drift pin 24.

As shown in FIG. 6, the third coupling metal fitting 40 couples two (upper and lower) vertical members 10, the first horizontal member 11, and the second horizontal member 12 to each other. The third coupling metal fitting 40 includes a shaft 41 and plates 42 that extend from the shaft 41. The first end of the shaft 41 is configured to be inserted into a tenon hole 10d of the upper vertical member 10. The second end of the shaft 41 is configured to be inserted into a tenon hole 10d of the lower vertical member 10. The plates 42 are located on an intermediate portion of the shaft 41. The number of plates 42 in the third coupling metal fitting 40 corresponds to the number of horizontal members that are to be coupled to each other. The plates 42 are configured to be inserted into the slit 11c of the first horizontal member 11 or the slit 12b of the second horizontal member 12. The plates 42 are fixed to the first horizontal member 11 or the second horizontal member 12 using drift pins 24.

As shown in FIG. 2, the building 1 includes frame members 50.

Each frame member 50 reinforces a wall having a Rahmen structure. The wall includes two vertical members 10 and a first horizontal member 11 or a second horizontal member 12 that extends across the two vertical members 10. One or more frame members 50 are arranged between two of multiple vertical members 10. Preferably, the thickness of each frame member 50 is equal to that of the wall structure.

Each frame member 50 is defined by dimensional lumbers 51. The cross-sectional area of each dimensional lumber 51 has a smaller cross-sectional area than those of the vertical member 10, the first horizontal member 11, and the second horizontal member 12. The frame member 50 is shaped into a rectangular frame using the dimensional lumbers 51. Each dimensional lumber 51 is made of wood in which the ratio of height to width is pre-defined in the market of woods used for construction. For example, in the cross-section of the dimensional lumber 51, the height is twice as long as the width. The thickness of the frame member 50 is equal to the height of the dimensional lumber 51.

The upper part of the frame member 50 is fixed to the first horizontal member 11 or the second horizontal member 12 using screws or bolts. The two sides of the frame member 50

are fixed to the vertical members **10** using screws or bolts. Preferably, the two sides of the frame member **50** are coupled using a coupling member **52**. The coupling member **52** is arranged between the two sides and connected to each of the two sides.

As shown in FIG. 7, the building **1** includes the floor **60** located between the upper and lower floors. The floor **60** is reinforced by the reinforcement members **63**.

The upper floor means a floor that is a level above the lower floor. For example, the floor **60** is located between the first and second floors. In another example, the floor **60** is located between the second and third floors. In a further example, the floor **60** is located between the first underground floor and the ground floors. In the present embodiment, the building **1** has two floors. The building **1** includes the floor **60** located between the first and second floors.

The floor **60** includes first floor extending members **61** and second floor extending members **62** that intersect the first floor extending members **61**. The first floor extending member **61** corresponds to one of the first horizontal member **11** and the second horizontal member **12** in the Rahmen structure. The second floor extending member **62** corresponds to the other one of the first horizontal member **11** and the second horizontal member **12** in the Rahmen structure.

The first floor extending member **61** and the second floor extending member **62** are made of wood. The reinforcement members **63** may be arranged between two first floor extending members **61**. The reinforcement members **63** may be arranged between two second floor extending members **62**.

As shown in FIG. 8, the reinforcement member **63** includes a plate-shaped body **65**, an upper flange **66**, and a lower flange **67**. The upper flange **66** is formed using a plate member. The upper flange **66** is located at the upper part of the body **65** so as to intersect the body **65**. The lower flange **67** is formed using a plate member. The lower flange **67** is located at the lower part of the body **65** so as to intersect the body **65**.

As shown in FIG. 7, the reinforcement members **63** are arranged between two second floor extending members **62** in the present embodiment. The two second floor extending members **62** each include support metal fittings **71** that support ends of the reinforcement members **63**. The reinforcement members **63** are supported by the support metal fittings **71** that are arranged at each of the two second floor extending members **62**. More specifically, the opposite ends of the reinforcement member **63** are respectively supported by the support metal fittings **71** from below. An end of the reinforcement member **63** is mounted on a support receiving portion **72** of each support metal fitting **71**. The end of the reinforcement member **63** is not fixed to the support metal fitting **71**. The end of the reinforcement member **63** is not fixed to the second floor extending member **62**. The reinforcement member **63** is arranged such that the end face of the reinforcement member **63** faces the side surface of the second floor extending member **62**. A gap may be provided between the end face of the reinforcement member **63** and the side surface of the second floor extending member **62**. When the building body **3** shakes, the reinforcement member **63** contacts the side surface of the second floor extending member **62**. This limits deformation of the Rahmen structure including the first floor extending members **61** and the second floor extending members **62**. A flooring material is arranged on the reinforcement members **63**. The reinforcement members **63** limits flexing of the flooring material.

As shown in FIG. 8, the support metal fitting **71** is configured to accommodate an end of the reinforcement member **63**. The support metal fitting **71** includes the

support receiving portion **72** and fixed portions **73**. The support receiving portion **72** supports the lower part of the end of the reinforcement member **63**. The fixed portions **73** extends from opposite ends of the support receiving portion **72**, respectively. The two fixed portions **73** are fixed to the first floor extending member **61** or the second floor extending member **62** using screws. The distance between the two fixed portions **73** is set such that the reinforcement member **63** can be inserted therebetween.

10 The first floor extending member **61**, the second floor extending member **62**, and the reinforcement member **63** are arranged such that their upper surfaces are flat surfaces flush with each other. This allows for the construction of a flat floor surface that includes the upper surfaces of the first floor 15 extending member **61** and the floor extending member **62**.

As shown in FIG. 9, the cross-section of the reinforcement member **63** is shaped so as to include a first portion **68** and second portions **69**. The first portion **68** extends vertically. The second portions **69** are arranged on opposite sides 20 of the first portion **68**, respectively, and intersect the first portion **68**. The first portion **68** corresponds to the body **65**. The upper second portion **69** on the upper side of the first portion **68** corresponds to the upper flange **66**. The lower second portion **69** on the lower side of the first portion **68** corresponds to the lower flange **67**.

The roof **4** will now be described with reference to FIGS. 10 to 14. The roof **4** is arranged on the building body **3**. The roof **4** has a truss structure. As shown in FIG. 10, the roof **4** includes roof frames **80**. In the present embodiment, the roof frames **80** each have a truss structure.

The roof frames **80** are arranged in parallel on the building body **3**. Preferably, the roof frames **80** are arranged at equal intervals. The roof frames **80** may be connected to each other by a coupling member **84** (see FIG. 13).

35 As shown in FIG. 11, the roof frame **80** includes a roof extending member **81**, rafters **82**, reinforcement members **83**.

The roof extending member **81** spans two first horizontal members **11** or two second horizontal members **12**. The 40 rafters **82** are coupled to the roof extending member **81**. In the present embodiment, the first ends of the two rafters **82** are coupled to each other so as to form a corner that has a predetermined angle. The second ends of the two rafters **82** are spaced apart from each other. The first end of the roof 45 extending member **81** is coupled to a portion near the second end of one of the two rafters **82**. The second end of the roof extending member **81** is coupled to a portion near the second end of the other one of the two rafters **82**. The roof extending member **81** and the two rafters **82** define the outer frame of the roof frame **80**. The reinforcement members **83** are coupled to the outer frame of the roof frame **80** such that a truss structure is formed in the outer frame of the roof frame **80**.

50 Preferably, the roof extending member **81**, the rafters **82**, and the reinforcement members **83** are formed using the dimensional lumbers **51**. The use of the dimensional lumbers **51** allows the roof frame **80** to have a standard thickness. When the roof frame **80** has a standard thickness, metal fittings being marketed can be used to fix the roof frame **80** to two first horizontal members **11** or two second horizontal members **12**.

55 The roof frame **80** is fixed to the first horizontal member **11** or the second horizontal member **12** using metal fittings. One of the first horizontal member **11** and the second horizontal member **12** to which the roof frame **80** is fixed is hereinafter referred to as the roof horizontal member **15**. The roof horizontal member **15**, to which the roof frame **80** is

fixed, is preferably thicker than a dimensional lumber. For example, the roof horizontal member 15, to which the roof frame 80 is fixed, has a cross-sectional area greater than that of the dimensional lumber. The roof horizontal member 15, to which the roof frame 80 is fixed, may be formed using a laminated wood.

Examples of the metal fittings include a first metal fitting 91 and a second metal fitting 95, which will be described below. The first metal fitting 91 and the second metal fitting 95 each fix the roof extending member 81 of the roof frame 80 to the roof horizontal member 15 at a portion where the roof extending member 81 of the roof frame 80 intersects the roof horizontal member 15.

As shown in FIG. 12, the first metal fitting 91 includes a fixed portion 92 and two tabs 93 that sandwich the roof extending member 81. The fixed portion 92 is fixed to the roof horizontal member 15. The two tabs 93 protrude from the fixed portion 92.

As shown in FIG. 13, the first metal fitting 91 may fix the coupling member 84, which couples two roof frames 80 to each other, to the roof horizontal member 15. More specifically, the first metal fitting 91 is arranged on the roof horizontal member 15 to sandwich the coupling member 84 at a portion where the coupling member 84 intersects the roof horizontal member 15.

As shown in FIG. 14, the second metal fitting 95 is an elongated metal plate. The second metal fitting 95 is hooked in contact with the upper surface of the roof extending member 81. Two opposite ends 96, 96 of the second metal fitting 95 are fixed to the roof horizontal member 15.

The method for constructing the building 1 will now be described.

The method for constructing the building 1 includes first to third steps. In the first step, the foundation 2 is formed. In the second step, the building body 3 having a Rahmen structure is formed on the foundation 2.

In the third step, pre-assembled roof frames 80 each having a truss structure are coupled to the building body 3. More specifically, each roof frame 80 includes rafters 82 and a roof extending member 81. The roof frames 80 are arranged on the building body 3 such that the roof extending members 81 extend across the roof horizontal members 15. The roof extending members 81 of the roof frames 80 are fixed to the roof horizontal members 15 of the building body 3 using metal fittings.

The method for constructing the building 1 may include a fourth step. In the fourth step, pre-assembled frame members 50 are used to reinforce a wall having a Rahmen structure. The fourth step may be performed in the second step or in the third step. More specifically, one or more frame members 50 are fitted between two vertical members 10, and the frame members 50 are fixed to the vertical members 10 using screws.

The method for constructing the building 1 may include a fifth step. In the fifth step, the reinforcement members 63 reinforce the floor 60 having a Rahmen structure. The fifth step may be performed in the second step or in the third step. For example, the support metal fitting 71 is coupled to each of the two second floor extending members 62 of the floor 60. The two support metal fittings 71 face each other. Each reinforcement member 63 is arranged on the space between the two support metal fittings 71, and the ends of the reinforcement members 63 are inserted into the support metal fittings 71 with the reinforcement members 63 brought down. In this manner, the reinforcement member 63 is arranged between the two second floor extending members 62.

The operation of the present embodiment will now be described.

Conventionally, there is room for improvement in the strength of the floor 60 for shaking in the horizontal direction. In the present embodiment, the first floor extending members 61 and the second floor extending members 62 are used to construct a frame assembly of the floor 60. In plan view, multiple reinforcement members 63 are arranged in the frame assembly. In one example, the reinforcement members 63 are arranged between two first floor extending members 61 parallel to each other. In another example, the reinforcement members 63 are arranged between two second floor extending members 62 parallel to each other. This prevents the frame assembly from being deformed by horizontal shaking of the building 1. Accordingly, the floor 60 is made more resistant to earthquake.

The advantages of the present embodiment will now be described.

- (1) The building 1 includes the floor 60, which is located between the upper and lower floors. The floor 60 includes multiple first floor extending members 61, which are made of wood, and multiple second floor extending members 62, which are made of wood. The reinforcement members 63 are arranged in at least one of the section between two first floor extending members 61 and the section between two second floor extending members 62. In this configuration, the reinforcement members further reinforce the frame assembly including the first floor extending members 61 and the second floor extending members 62. This makes the floor 60 more resistant to earthquake.
  - (2) Two first floor extending members 61 may each include the support metal fittings 71, which support the ends of the reinforcement members 63. The reinforcement members 63 are supported by the support metal fittings 71, which are arranged at each of the two first floor extending members 61. This configuration allows the floor 60 to be reinforced through a simple attachment task.
  - (3) Two second floor extending members 62 may each include support metal fittings 71, which support the ends of the reinforcement members 63. The reinforcement members 63 are supported by the support metal fittings 71, which are arranged at each of the two second floor extending members 62. This configuration allows the floor 60 to be reinforced through a simple attachment task.
  - (4) The cross-section of each reinforcement member 63 is shaped so as to include the first portion 68 and the second portions 69. The first portion 68 extends vertically. The second portions 69 are arranged on opposite sides of the first portion 68, respectively, and intersect the first portion 68. This configuration reduces flexing of the floor 60 in the vertical direction.
  - (5) In the building 1, the first floor extending members 61, the second floor extending members 62, and the reinforcement members 63 are arranged such that their upper surfaces are flat surfaces flush with each other. This configuration defines a flat floor surface.
- The above embodiment exemplifies, without any intention to limit, an applicable form of a building. The building 1 exemplified in the embodiment can take a form different from that illustrated in the embodiment. For example, some of the components of the embodiment may be replaced, changed, or omitted. Alternatively, another component may be added to the embodiment. Modifications of the embodiment will now be described.

In the building 1 of the present embodiment, the vertical members 10 is arranged upright on the foundation 2. Instead, the vertical members 10 may be arranged upright on a base that is arranged above the upper side of the foundation 2.

The roof frames 80 may be coupled to the roof horizontal members 15 using metal fittings that are similar to the first coupling metal fittings 30 or the second coupling metal fittings 36.

REFERENCE SIGNS LIST

1) Building; 60) Floor; 61) First Floor Extending Member; 62) Second Floor Extending Member; 63) Reinforcement Member; 68) First Portion; 69) Second Portion; 71) Support Metal Fitting

The invention claimed is:

1. A building comprising a floor located between an upper floor and a lower floor, wherein
  - the floor includes first floor extending members and second floor extending members that intersect the first floor extending members,
  - the first floor extending members and the second floor extending members are made of wood,
  - a reinforcement member is arranged in at least one of a section between two of the first floor extending members and a section between two of the second floor extending members,
  - each of the two of the first floor extending members defining the section that the reinforcement member is arranged in includes a support metal fitting that supports an end of the reinforcement member, and/or each of the two of the second floor extending members defining the section that the reinforcement member is arranged in includes a support metal fitting that supports an end of the reinforcement member,

the second floor extending members include a short second floor extending member and long second floor extending members being longer than the short second floor extending member,

the short second floor extending member is arranged between the long second floor extending members, the short second floor extending member includes a first side surface,

one of the long second floor extending members includes a second side surface,

the first side surface is opposed to the second side surface, the support metal fitting is arranged on each of the first side surface and the second side surface,

the reinforcement member is arranged between the short second floor extending member and the one of the long second floor extending members,

the end of the reinforcement member is supported by the support metal fitting, and

the reinforcement member is not fixed to the support metal fitting, the short second floor extending member, and the long second floor extending members.

2. The building according to claim 1, wherein
  - a cross-section of the reinforcement member is shaped so as to include a first portion extending vertically and a second portion arranged on each of opposite sides of the first portion and intersecting the first portion.

3. The building according to claim 1, wherein
  - the first floor extending members, the second floor extending members, and the reinforcement member are arranged such that upper surfaces of the first floor extending members, upper surfaces of the second floor extending members, and an upper surface of the reinforcement member are flat surfaces flush with each other.
